UNITED STATES PATENT OFFICE.

JAMES H. STRUGNELL, OF TORONTO, CANADA.

DESIGN FOR A CHILD'S PLATE.

SPECIFICATION forming part of Design No. 32,025, dated December 26, 1899.

Application filed November 27, 1899. Serial No. 738,481. Term of patent 14 years.

To all whom it may concern:

Be it known that I, JAMES H. STRUGNELL, a subject of the Queen of Great Britain, and a resident of Toronto, in the Province of Ontario and Dominion of Canada, have invented a new and original Design for a Child's Plate, of which the following is a full, clear, and exact specification.

Reference is to be had to the accompanying drawings, forming a part of this specification, in which similar characters of reference indicate corresponding parts in both the views.

Figure 1 is a plan view of a child's plate, showing my design; and Fig. 2 is a sectional side elevation of the same on the line 2 2 in Fig. 1.

The invention relates to tableware.

The design in its entirety consists of a circular bottom A, having a perpendicularly-rising flange B and an ogee rim C extending from the upper edge of the flange B in an outward and downward direction, the lower

edge of the rim being in a plane with the under side of the bottom A, as plainly shown in Fig. 2, the rim appearing on diametrically opposite sides with cut-out portions D.

The leading feature of the design consists of the bottom having the flange and the downwardly and outwardly curved rim, and a minor feature of the design consists of the flange rising perpendicularly from the bottom of the plate.

Having thus fully described my invention, I claim as new and desire to secure by Letters Patent—

The design for a child's plate, as herein shown and described.

In testimony whereof I have signed my name to this specification in the presence of two subscribing witnesses.

JAMES H. STRUGNELL.
